GLASS LIFTING MECHANISM FOR
HURRICANE LAMPS

Pierre François Marie Pitavy, Chalon-sur-Saône,
France, assignor to Société Anonyme dite: So-
ciété Industrielle de Ferbianterie, Paris, France,
a corporation of France

Application June 1, 1951, Serial No. 229,365
In France September 15, 1950

3 Claims. (Cl. 240—32)

1

Hurricane lamps are already known in which the bail is availed of for the purpose of moving the bulb-shaped glass chimney up and down in order to light the lantern. More specifically, a particular hurricane lantern type is known in which the bail can overturn freely to one side of the lantern as well as through a portion of its possible displacement towards the other side, the remainder of this latter possible displacement being availed of to lift the glass.

My invention is concerned with a hurricane lamp of the kind described which is provided with a simple and cheap glass-lifting mechanism, the whole of which is enclosed in the lantern and consequently removed from any risk of injury.

The lamp glass is moved up and down through the medium of a chimney which surmounts the same, and my invention also extends to means whereby said glass is removably secured to said chimney.

A lamp according to my invention will now be described more specifically hereinafter, reference being had to the appended drawings in which:

Figure 1 is a sectional view taken on the axis of the top portion of the lantern and shows the parts at the beginning of the glass-lifting action.

Figure 2 is a similar sectional view taken at right angles to Fig. 1.

Figure 3 is a fractional plan view of Fig. 1.

Figure 4 is a sectional view taken on the axis of the top portion of the lantern and shows the parts at the completion of the glass-lifting action.

Figure 5 is a further sectional view taken on the axis of the top portion of the lantern ready for use, i. e. with the chimney lowered and with its bail fully dropped to that side where its fall is unrestricted.

Figure 6 is a bottom plan view of the chimney with the glass removed.

Figure 7 is a sectional view taken on line X—X in Fig. 6.

Figure 8 is an elevational view of the top portion of the glass.

Figure 9 is an elevational, partly sectional, view of the connection of the glass with the movable chimney.

Figure 10 is a sectional view taken on line Y—Y in Fig. 9.

The framework of the lamp comprises a bonnet which includes an outer stamped metal barrel 1 secured to the top ends of a pair of tubular uprights 2 and in which is hinged at 3 the lantern

2

bail 4 while its neck 5 serves as a guide for the slidable chimney 6.

5 A further barrel-like part 7 stamped to asymmetrical U-section is fitted in and secured to said outer barrel 1. Said member 7 serves as a guide for a ferrule 8 rigid with the slidable chimney, so that the latter is guided at two places.

10 A coil spring 9 abutting at its top end against the neck 5 of the fixed outer barrel 1 and at its bottom end against the ferrule 8 downwardly urges the whole slidable chimney assembly composed of said ferrule 8, chimney 6 and a cover 10 on the latter.

15 The two ends 11 (see Fig. 3) of the bail 4 project through a pair of longitudinal slots 12 cut in ferrule 6 and are bent twice and interconnected by a sleeve 13, the bail ends assembled in this manner thus having the trapezoidal outline shown in Fig. 3. Arranged within the slidable chimney is a spring wire clip 14 the two legs 15 of which are kept engaged at the ends 16 thereof and by their own resiliency in a pair of holes in the ferrule 8.

20 As shown more particularly in Fig. 4, the double bend 11—13—11 formed by the ends of the bail 4 is located in a plane which intersects a certain angle with that of the bail proper in order that the slidable chimney shall be locked in its lifted position when the bail is swung down to its 25 chimney lifting position.

25 The operation of the device is as follows:

Referring again to Fig. 2, C—D—E in dash and dot lines denotes the arc over which the bail is freely movable, i. e. remains inoperative, in either 30 direction; C—F—G denotes the arc over which the bail is effective to lift the slidable chimney when swung down in the direction of the arrow f; the bail is shown in its position at the beginning of its chimney-lifting action. The bail 4 is 35 as already stated is swingably mounted in bearing holes or eyelets 3 punched through the outer barrel 1. The hook or wire clip 14 is caught by the sleeve 13 and becomes effective through the ends 16 of the legs 15 to lift the movable chimney against the action of the loading spring 9.

40 At the completion of the glass-lifting stroke, the bail 4 and the slidable chimney 8—6—10 occupy the position illustrated in Fig. 4, in which the triangle a—b—c formed by the lines through the three centres 13, 3 and 16 clearly shows that the chimney is positively kept in its lifted position since the link system a—b—c is locked, 45 owing to the fact that the line a—c in the direction of which the action spring 9 is exerted assumes a position beyond the line b—c along

50 55

which said action is resisted. In order to restore the chimney to its dropped position it is only necessary to slightly pull the bail upwards contrawise to the direction of the arrow *f* and against the action of the spring, whereafter the remainder of the restoration process will be taken care of by the spring.

It will be appreciated that with the exception of the unavoidable shifting of the chimney in its guides *5* and *7* the whole operation of the mechanism only involves pivotal motions, whereby friction is reduced to a minimum.

With the lantern glass removed from its mounting, the downward stroke of the slideable chimney is limited by the length of the slots *12* through which project the ends *11* of the bail.

The means whereby the glass *17* of the lantern is secured to the ferrule *8* rigid with the slideable chimney are shown in Figs. 6 to 10.

The glass *17* is formed at its top end with a bead *18* which delimits a guide bevel *20* and a groove *19*. On the other hand, the ferrule *8* is formed at its lower edge with a bent-in portion *21* in which a wire spring *22* is received the two free ends of which are shown at *23*. The said wire spring *22*, which is retained by its own resiliency within the bent-in portion *21* is formed with straight slightly secant sections *24* (see Figs. 6 and 10) adapted to cooperate with the bead *18* on top of the glass *17* in the fashion of the female and the male portions of a pressure button.

In fixing the glass to the bonnet, it is only necessary to lay the former upright on the grid of the lantern and to depress the slideable chimney with the aid of the bail, for the purpose of which the resistance opposed by the coil spring *9* should be sufficiently high to allow the wire spring *22* to swallow the bead *18* and get home into the groove *19* of the glass. When it is desired to detach the glass *17* from the chimney, it is only necessary to keep the glass pressed by its lower part upon the grid of the lantern and to swing the bail in glass-lifting direction, as a result of which the wire spring *22* is slipped once more past the bead *18* and consequently the glass is released from the slideable chimney.

It is to be understood that this lamp glass coupling device is only given by way of example and it can be substituted by any equivalent means involving the cooperation of a bead at the top end of the glass providing a groove for the accommodation of a member rigid with the chimney *8* adapted to snap thereinto.

I claim:

1. A hurricane lamp comprising a fixed bonnet, a vertically slideable chimney mounted in said bonnet, a loading spring interposed between said fixed bonnet and said slideable chimney, a swingable bail hinged to the bonnet formed with-

in the chimney with a double bend, a pair of diametrically opposite longitudinal slots in the wall of the chimney for the bail to project therethrough and a double-armed V-shaped clip within the chimney, hinged by its arms to the latter at the base thereof and separate from the double bend of the bail, the apex of the V-shaped clip being return-bent to provide a hook positioned in the path of swinging movement of the double bend upon rotation of the bail.

2. A hurricane lamp comprising a fixed bonnet, a vertically slideable chimney mounted in said bonnet, a loading spring interposed between said fixed bonnet and said slideable chimney, a swingable bail hinged to the bonnet formed with in the chimney with a double bend in a plane at an angle to that of the bail proper, a pair of diametrically opposite longitudinal slots in the wall of the chimney for the bail to project therethrough, a double-armed V-shaped clip within the chimney, hinged by its arms to the latter at the base thereof and separate from the double bend of the bail, the apex of the V-shaped clip being return-bent to provide a hook positioned in the path of swinging movement of the double bend upon rotation of the bail, and means at the bottom end of the slideable chimney to detachably connect the lamp glass therewith.

3. A hurricane lamp comprising a fixed bonnet, a vertically slideable chimney mounted in said bonnet, a loading spring interposed between said fixed bonnet and said slideable chimney, a swingable bail hinged to the bonnet and formed within the chimney with a double bend in a plane at an angle to that of the bail proper, a pair of diametrically opposite longitudinal slots in the wall of the chimney for the bail to project therethrough, a double-armed V-shaped clip within the chimney, hinged by its arms to the latter at the base thereof and separate from the double bend of the bail, the apex of the V-shaped clip being return-bent to provide a hook positioned in the path of swinging movement of the double bend upon rotation of the bail, a lamp glass formed at its top edge with a bead defining a guide bevel at its margin and a groove immediately below said bead, a peripheral recess on the inside of the lower end of said slideable chimney and a resilient wire positioned in and having a portion projecting at least in part from said recess, said wire being resiliently biased toward the center of said chimney.

PIERRE FRANÇOIS MARIE PITAVY.
